UNITED STATES PATENT OFFICE.

EMILE FRANTZ, OF SAN FRANCISCO, CALIFORNIA.

SOUND-PRODUCING DEVICE.

Application filed February 3, 1925. Serial No. 6,669.

To all whom it may concern:

Be it known that I, EMILE FRANTZ, citizen of the United States, residing at San Francisco, county of San Francisco, State of California, have invented new and useful Improvements in Sound-Producing Devices, of which the following is a specification.

My invention has for its object means for securing an amplification of the sound from a telephone receiving mechanism, and is especially adapted to what is known as a loud speaking apparatus for radio and telephone communication.

Other objects will appear from the drawing and specifications which follow.

These objects I attain by a plurality of diaphragms operated in synchronism from a single armature which is positioned in a magnetic field, and which field is varied by electrical impulses corresponding with sound wave vibrations which it is desired to transform and reproduce as sound at another point.

The vibration of the plurality of diaphragms establishes a sound wave through suitably arranged passageways.

Adjusting means are provided for varying the resiliency of the diaphragms jointly.

Referring to the accompanying drawings, Fig. 1 is a cross section through a loud speaking device employing my invention.

Fig. 2 is similar to Fig. 1 but showing a variation in the adjusting means and of the sound amplifying passageways with certain of the parts left out.

Fig. 3 is a section of Fig. 1 on the line III-III with the sound tubes removed.

Fig. 4 is a medial section through one of the diaphragms corresponding with a relatively loose adjustment.

Fig. 5 is similar to Fig. 4 but corresponding with a relatively tight adjustment.

Fig. 6 is an enlarged cross section of a conventional single diaphragm.

Fig. 7 is a diagram of a pair of diaphragms, the sum of whose thicknesses is equal to the thickness of the single diaphragm, Fig. 6.

Fig. 8 is a diagrammatic showing of a conventional sound vibration as produced by 50 the diaphragms of Fig. 6 and Fig. 7.

Throughout the figures similar numerals refer to identical parts.

The numerals 1, 2 indicate sections of a coil surrounding the magnetic field 8 and 55 adapted to be connected in any conventional telephone circuit.

3 and 4 are the poles of the circular permanent magnet 5 having end pieces 6, 7 respectively, whereby a varying magnetic field 60 is established in the space 8 which actuates the armature 9.

At 10 and 11 are a pair of diaphragms connected together and to the armature 9 by the bar 12, whereby the diaphragms 10, 11 are 65 caused to vibrate in synchronism with the armature 9 and to reproduce the variations in the magnetic field 8 transmitted from the telephone circuit, which circuit is not shown but well known; and in which the coil 1, 2 70 is connected.

The diaphragm 10 is mounted between supporting ring members 13, 14 and the diaphragm 11 between similar ring members 15, 16.

The rings are supported respectively between outside and inside plates 17, 18 and 75 19, 20.

Between the plates 18 and 20 are a plurality of supporting bars 21, in compression.

Outside plates 22, 23 are held together by a plurality of tension members 24.

Plates 22, 23 are carried upon the tubes 25, 26 provided with external right and left threads with which the plates 22, 23 engage.

By rotating the plates 22, 23, on threaded tubes 25, 26, their corresponding end plates 17, 19 respectively will be compressed more or less against rings 13 and 16 establishing a relatively looser or tighter gripping of 90 the diaphragms 10 and 11 between the rings 13, 14 and 15, 16, the purpose of which is more clearly set forth below.

From the tubes 25, 26 conduits 27, 28 convey the sound impulses from the diaphragms 95 10, 11 respectively and these impulses may

be brought together in the throat member 29 and amplified by the flaring tube 30.

In Fig. 2 the end plates are shown at 40, 41 and an adjusting plate is shown at 43 carried on a threaded thimble member 44, mounted on the threads 42 of the sound tube 45.

The outer plates 43 and 41 are connected by a plurality of tension members 46 and a 10 rotation of the single thimble 44 varies the pressure between the diaphragm rings 13, 14 and 15, 16 held between the plates 18 and 20 by the compression members 21.

At 47 is shown a flaring form of discharge 15 throat and amplifying sound dispersion member 48.

Rings 13, 14 and 15, 16 are preferably made of resilient material and I have found rubber to be well adapted to this use as 20 it enables the diaphragm therebetween to be gripped with greater or less tightness, according to the compression of the rings.

In Fig. 4 the diaphragm 10 is shown distorted between loosely compressed rings 13, 25 14 and in this instance the diaphragm acts as a beam supported at each end whereas in Fig. 5 the diaphragm is shown distorted under equivalent impulses when tightly 30 gripped between the more heavily compressed rings 13, 14 in which case the diaphragm distortion will correspond with the bending of a beam fixed at each end. The degree of bending or distortion will be greater in the case of Fig. 4 than in the 35 case of Fig. 5, for equal loading or impulse.

The diaphragm of Fig. 5 will be more highly resilient and will respond with greater accuracy to high notes whereas the diaphragm adjusted as shown in Fig. 4 will 40 better respond to and reproduce low notes.

The intensity of the sound wave will be proportional in any instance to the amplitude of the diaphragm vibration, and the degree of the diaphragm distortion will be 45 proportional to the variations of the magnetic field and therefore to the electrical impulse in the coil 1, 2.

If a single diaphragm be employed, and 50 the entire effort of the armature be expended thereon and the amplitude of diaphragm movement or vibration will be indicated by the curve 50 of Fig. 8 and if the thickness of the said diaphragm corresponds with the thickness or dimension 51 55 of Fig. 6, then the amplitude of the vibration of each of the diaphragms of Fig. 1 under an equivalent electric impulse and where the thickness of said diaphragms is one-half of the thickness 51 as indicated at 52, 53 of Fig. 7 will have an amplitude of the vibration corresponding with the curve 54 of Fig. 8; in other words, with the same electrical impulse my pair of diaphragms 60 will each vibrate with an amplitude twice as great as where a single diaphragm of

the same diameter and twice the thickness is employed.

This is true, because the resistance to bending which must be overcome by the action of the magnetic field will be proportional to 70 the square of the thickness of the diaphragm. My two diaphragms each being one-half the thickness of a single diaphragm will each offer a resistance one quarter that of the thick diaphragm and the sum of these two 75 will be one-half that of the thick diaphragm.

With an equivalent impulse I will therefore attain twice the amplitude of vibration in each of the two diaphragms.

The amplitude of the diaphragm vibration determines the magnitude of the sound wave, and as each of my two diaphragms will, under a given electric impulse, have twice the amplitude of vibration the sound wave combined from the two will be very 80 much greater than in the case of a single diaphragm, and except for other losses as friction, eddy currents, etc, the resulting sound impulse will be four times as great 85 as with a single diaphragm.

The sound waves from the two diaphragms 10, 11 may be combined in a single throat piece 29 and amplified by the tube 30, or the tube members 45, 47 may be employed and each amplified through a separate dispersion element one of which is shown at 48 or any combination of amplifying and dispersion device may be employed to suit the taste and requirements of any 90 given case.

My invention is directed to the attainment of increased sound waves from a given magnetic field, and with my plurality of diaphragms and adjusting means for said diaphragms, any form of magnetic field device or sound dispersion means may be employed in combination therewith.

Also other means of adjusting the supporting rings of the diaphragms and other connecting means between the diaphragms 105 may be employed without departing from the spirit of my invention and I wish to be understood as claiming all such variations.

I claim:

1. A sound producing device comprising 110 a frame and means supported thereby adapted to establish a magnetic field, a circuit adapted to vary said field, an armature within said field, a plurality of diaphragms gripped in said frame and link means between said diaphragms and said armature whereby said diaphragms are constrained to vibrate in synchronism with said armature in response to the variations of said field, resilient rings about the peripheries 115 of said diaphragms and screw actuated means constructed and adapted to variably compress said rings against said diaphragms and including an outside and inside plate 120 for each diaphragm and a plurality of com- 125

pression struts between said inside plates and a plurality of tension members between said outside plates.

2. A sound producing device as set forth in claim 1 wherein said armature is positioned between said diaphragms and a sound tube embraces each diaphragm opposite said armature.

3. A sound producing device as set forth in claim 1 wherein said armature is positioned between said diaphragms and a sound tube embraces each diaphragm opposite said armature and an amplifying throat member into which said tube discharges.

EMILE FRANTZ.
